DEVICE FOR THE MANUFACTURE OF EXTRUSION PRESS BRICKS HAVING THE APPEARANCE OF CAST BRICKS

Mor Josef Singer, The Hague, Netherlands, assignor to Nederlandse Organisatie Voor Toegepast - Natuurwetenschappelijk Onderzoek Ten Behoeve Van Nijverheid, Handel en Verkeer, The Hague, Netherlands, a corporation of the Netherlands

Application October 2, 1951, Serial No. 249,342

Claims priority, application Netherlands October 2, 1950

6 Claims. (Cl. 25—1)

1

Extrusion press bricks, flooring tiles and such like are more suitable for a fully automatic and mechanized production and of better quality than hand formed bricks or cast bricks.

As the strand is pressed out through a mouth piece and is then cut up, extrusion press bricks have a smooth surface. The disadvantage hereof is that facades made with these bricks have a less attractive appearance so that many consumers object to their use.

It is the main object of this invention to provide a device by which extrusion press bricks are obtained of the same surface structure as cast bricks or machine made cast bricks.

Means of similar kind have been proposed before. In the Dutch patent specification No. 4,924 a device has been described in which a roller is used for roughening the strand; the surface of said roller is roughened or profiled to provide surfaces like those of hand formed bricks, while moreover scratches can be made in the strand by means of chains provided with spikes, which spikes periodically are disengaged from the strand of clay, but the bricks obtained by this process are in the main very similar, because the same pattern is always repeated, and this type of brick has not become popular.

In the British patent specification No. 173,665 also a modified surface structure is given to material that is pressed through a mouth piece. These patterns however, are also repeated constantly.

In the British patent specification No. 195,280 a device is described by which a thin layer of the surface is cut off from the strand, which thin layer is again united afterwards with the core by means of pressure.

It is also known to treat the surface of the strand with rotating brushes which serve to provide to the surface a somewhat rough appearance; however, the folds and corrugations of hand formed bricks cannot be imitated in this way.

According to the invention the surface of the strand is treated with rollers covered with metal turnings or helical coils of different diameter and speed, said turnings or coils being fastened onto the surface of the roller in such a way, that, owing to the pressure of the roller they make deviating movements against the strand. These deviating movements are so irregular that bricks, manufactured in this way have the same varied appearance as cast bricks. The metal turnings do not only press into the clay but have also a carving effect, causing irregular incisions in

the surface of the clay; these incisions may, if desired, be partly flattened by a second, smoothly surfaced roller, by which treatment irregular folds and corrugations are produced, so that the appearance of hand formed bricks is closely approximated in this way.

As a rule two horizontally and two vertically arranged rollers with turnings or coils will be applied so that only the surface of the brick that has the largest area (i. e. the plane perpendicular to the longitudinal axis) is not treated.

Another advantage of this device is that the metal turnings or coils are resilient so that an elastic pressure is exerted upon the surface of the strand without necessitating special constructions for a sprung fitting of the roller.

The strand may be sprinkled with sand in the usual way, to impart to the bricks the "grained" effect of hand formed bricks. Moreover also other substances may be applied such as fine sand, dyes (metal oxides) and the so called engobes.

In the annexed drawing the device of the invention is shown schematically.

In the accompanying drawings Figure 1 represents a side view of a device according to the invention. Figure 2 is a view of the roller 3 of Figure 1.

In Figure 1 only the rollers above the strand are indicated. Number 1 represents a strand as pressed from the mouth piece 2 of the extrusion press. Number 3 shows the roller covered with metal turnings 4, treating the upper surface of the strand. Number 5 is a smoothly surfaced roller which serves to partly flatten the incisions. Rollers supporting the strand are represented by number 6.

In Figure 2 the roller is indicated with 3; metal turnings or coils 4 are fastened to the surface of said roller.

40 I claim:

1. In an apparatus for treating the surface of extrusion press bricks, in combination, a roller; and a plurality of helical springs haphazardly arranged and secured to the surface of said roller.

2. In an apparatus for treating the surface of extrusion press bricks, in combination, a roller; and a plurality of helical springs haphazardly arranged and secured to the surface of said roller, at least some of said springs being of different tension.

3. In an apparatus for treating the surface of extrusion press bricks, in combination, a roller; and a plurality of helical springs haphazardly arranged and secured to the surface of said roller, at least some of said springs having con-

3

convolutions at different distances apart than the convolutions of the other of said springs.

4. In an apparatus for treating the surface of extrusion press bricks, in combination, a roller; and a plurality of helical springs haphazardly arranged and secured to the surface of said roller, at least some of said springs having a different tension and having convolutions at different distances apart than the convolutions of the other of said springs.

5. In an apparatus for treating the surface of extrusion press bricks, in combination, a roller; and a plurality of helical springs haphazardly arranged and secured to the surface of said roller at each end of each of said springs.

6. In an apparatus for treating the surface of extrusion press bricks, in combination, a smooth surfaced roller; and a plurality of helical springs haphazardly arranged and secured to the surface of said roller.
